CLAIM

The ornamental design for a cofferdam module, as shown and described.

DESCRIPTION

FIG. 1 is a front perspective view of a first embodiment of a cofferdam module;

FIG. 2 is a left side elevation view thereof;

FIG. 3 is a right side elevation view thereof;

FIG. 4 is a front elevation view thereof;

FIG. 5 is a back elevation view thereof;

FIG. 6 is a top plan view thereof;

FIG. 7 is a front perspective view of a second embodiment of a cofferdam module;

FIG. 8 is a left side elevation view thereof;

FIG. 9 is a right side elevation view thereof;

FIG. 10 is a front elevation view thereof;

FIG. 11 is a back elevation view thereof; and

FIG. 12 is a top plan view thereof.

FIG. 13 is a front perspective view of a third embodiment of a cofferdam module;

FIG. 14 is a left side elevation view thereof;

FIG. 15 is a right side elevation view thereof;

FIG. 16 is a front elevation view thereof;

FIG. 17 is a back elevation view thereof; and

FIG. 18 is a top plan view thereof.
